UNITED STATES PATENT OFFICE.

PERCY R. SAUNDERS, OF ANTIGONISH, NOVA SCOTIA, CANADA.

PISTOL-CLAMP.

1,278,027.

Specification of Letters Patent. Patented Sept. 3, 1918.

Application filed June 6, 1918. Serial No. 238,509.

To all whom it may concern:

Be it known that I, PERCY R. SAUNDERS, a subject of the King of Great Britain, residing at Antigonish, in the Province of Nova Scotia, Dominion of Canada, have invented a new and useful Pistol-Clamp; and I do hereby declare the following to be a full, clear, and exact description of the invention, such as will enable others skilled in the art to which it appertains to make and use the same.

The present invention relates to a pistol attaching means for guns, and has for its object to provide a device of this character which embodies novel features of construction whereby a pistol can be securely mounted upon the barrel of a military rifle and actuated when the rifle is in position for a bayonet charge without the necessity of shifting or releasing the grip upon the fore arm and stock.

Further objects of the invention are to provide a pistol attaching means for rifles which can be utilized to secure any standard make or construction of pistol to the barrel of any standard gun, which supports the pistol in such a position that the shots fired therefrom will clear a bayonet fixed upon the muzzle of the gun, and which will admit of the pistol being actuated while making a bayonet charge without interfering with the necessary firm grip upon the gun, and which will thereby practically double the offensive powers of the soldier when making a bayonet charge.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawings, in which:—

Figure 1 is an enlarged side elevation of a pistol supporting bracket constructed in accordance with the invention, showing the same as utilized to mount an automatic pistol upon a gun and barrel, portions being broken away.

Fig. 2 is a front elevation of the pistol supporting means.

Fig. 3 is a plan view of the handle clamping ring of the pistol supporting means.

Fig. 4 is a sectional view through a portion of the pistol supporting bracket, taken on the line 4—4 of Fig. 1, and

Fig. 5 is a side elevation of a military rifle provided with an auxiliary pistol which is mounted upon the barrel thereof by a pistol supporting bracket constructed in accordance with the present invention.

Corresponding and like parts are referred to in the following description and indicated in all the views of the drawings by the same reference characters.

Referring to the drawings, the reference character A designates a conventional military rifle which is adapted to have a bayonet B fixed upon the muzzle end of the barrel thereof so that the rifle can be used effectively in a bayonet charge. In accordance with the ideas of the present invention an auxiliary pistol C, preferably having an automatic action, is mounted upon the barrel of the gun in such a position that the shots from the pistol will clear the bayonet, said pistol being adapted to be fired by means of a finger piece 1 which can be manipulated by the hand grasping the fore arm of the rifle without the necessity of releasing or shifting the grip of the soldier upon the rifle. The soldier can thus use the pistol as well as the bayonet and the effectiveness of the rifle for offensive purposes is practically doubled. The supporting bracket may be of any suitable construction, being shown in the present instance as including a clamping band 2 which fits around the handle of the pistol C and engages a frame D extending upwardly on one side of the pistol and rigidly secured to the barrel of the rifle by means of clamps 3. This frame D is shown as provided at the lower end thereof with a tang 4 which enters a socket 5 at the front end of the clamping band 2 and is rigidly fastened therein by a set screw 6. The upper end of the frame terminates in two spaced arms 7 which are rigid with the lower halves of the hinged clamping members 3. The clamping members 3 are shaped to fit around the barrel of the rifle and the jaws thereof terminate at their free ends in outstanding ears 8 which are connected by clamping bolts 9. This construction enables the bracket to be rigidly secured to the gun barrel, and the pistol C is supported under the gun barrel in a parallel relation thereto

so that the shots fired therefrom will have the same general direction as the rifle barrel and clear the bayonet B. The lower portion of the frame D is formed with a 5 channel shaped side bar 10 which receives the trigger guard of the pistol C and is shaped to fit around the same. A set screw 11 is threaded in this channel shaped side bar 10 of the frame and arranged to engage 10 the trigger guard of the pistol, said set screw coöperating with the handle clamp, 2 to hold the pistol C firmly in position without interfering with the proper functioning of the different parts of the pistol. 15 There are no set screws or clamping members to engage the barrel of the pistol, and the latter is free to slide rearwardly under the recoil of the discharge if the pistol should be of that type which includes a 20 slidably mounted barrel.

The finger piece 1 for firing the pistol is pivotally connected at 12 to the rear end of a rod 13 which extends along the side of the gun barrel, the forward end of the 25 rod being offset downwardly at 14 and loosely received within a pair of ears 15 projecting from the frame D. The pivotal mounting of the finger piece 1 enables it to be folded when not in use, as indicated 30 by dotted lines on Fig. 1, and a spring 16 normally tends to slide the rod 13 forwardly to hold a trigger operating arm 17 in inoperative position. The arm 17 is arranged to be normally positioned directly in front 35 of the trigger 18 of the pistol C, the upper end of the arm being bifurcated and formed with a pair of sleeves 19 which are adjustable upon the rod 13. Set screws 20 may be utilized to hold the sleeves 19 in an adjusted 40 position, and the arrangement is such that the arm 17 is out of engagement with the trigger 18 under normal conditions, although by pulling rearwardly upon the finger piece 1 the arm 17 can be brought into engagement with the trigger 18 and the pistol fired in the usual and well-known manner. As 45 soon as the finger piece 1 is released the parts will be returned to their normal position by the action of the spring 16, and where the pistol C is automatic in its action 50 the pistol is ready to be again fired by a further pull upon the finger piece. The rear end of the slide 13 may pass through a suitable guide member 21 upon the fore arm 55 of the rifle, thereby holding the rod in proper position and directing the same in its sliding movements. The finger piece 1 can be readily engaged by one of the fingers of the hand which grasps the fore arm of 60 the stock when the rifle is in position for a bayonet charge. It will thus be obvious that the pistol can be fired without bringing the gun to the shoulder and without moving the same from the bayonet charge position 65 or even shifting the grip of the hands.

thereon. A soldier thus equipped will have much greater confidence in himself, for the reason that the offensive powers of his rifle are practically doubled and he has a great advantage over an adversary whose gun is 70 merely equipped with a bayonet and can only be fired by shifting the grip thereon in a manner which would be very dangerous in making a bayonet charge at close quarters.

Having thus described the invention, what 75 I claim as new and desire to secure by Letters Patent, is:—

1. The combination with a gun and a pistol, of a pistol supporting bracket including a side frame arranged at one side of the 80 pistol and provided at its upper end with clamping means to engage the barrel of the gun and at its lower end with clamping means for engaging the handle of the pistol, guide members projecting from the side 85 frame, a rod slideable within the guide members and extending rearwardly along the gun to the stock thereof, a trigger operating arm carried by the rod and projecting in front of the trigger of the pistol, and a 90 finger piece at the rear end of the rod.

2. The combination with a gun and a pistol, of a clamping member engaging the handle of the pistol, a side frame extending upwardly on one side of the pistol and rigid 95 with the handle clamp, means on the side frame for engaging the trigger guard of the pistol, clamping members at the upper end of the side frame for engaging the gun barrel, a slide mounted upon the side frame, 100 a trigger operating arm carried by the slide and projecting in front of the trigger of the pistol, and means for operating the slide from the stock of the gun.

3. The combination with a gun and a pistol, of a clamping member engaging the handle of the pistol, a side frame rigid with the clamping member and extending upwardly on one side of the pistol, said side 105 frame being formed with a channel shaped 110 bar receiving the trigger guard of the pistol, clamping means at the upper end of the side frame for engaging the gun barrel, a slide mounted upon the side frame, a trigger 115 engaging arm carried by the slide and projecting in front of the trigger of the pistol, and means for operating the slide from the stock of the gun.

4. The combination with a gun and a pistol, of a clamping member engaging the 120 handle of the pistol and formed with a socket, a side frame formed with a tang which is clamped within the socket of the handle clamp, said frame extending upwardly on one side of the pistol and being 125 provided with means for engaging the trigger guard of the pistol, clamping means at the upper end of the frame for engaging the gun barrel, a slide mounted upon the frame, a trigger engaging arm carried by the slide 130

and projecting in front of the trigger of the pistol, and means for operating the slide from the stock of the gun.

5. The combination with a gun and a pistol, of a clamping member engaging the handle of the pistol, a side frame rigid with the clamping member and extending upwardly on one side of the pistol, said side frame being formed with a channel shaped bar receiving the trigger guard of the pistol, a set screw threaded in the channel shaped bar and engaging the trigger guard, clamping means at the upper end of the side frame for engaging the gun barrel, a slide mounted upon the frame, a trigger engaging arm carried by the slide, and means for operating the slide from the stock of the gun.

6. The combination with a gun and a pistol, of a clamping member engaging the pistol handle and formed with a socket, a

side frame formed with a tang which is clamped within the said socket, said frame extending upwardly on one side of the pistol and being formed with a channel shaped member receiving the trigger guard of the pistol, a set screw threaded in the channel shaped member and engaging the trigger guard, clamping means at the upper end of the side frame for engaging the gun barrel, a slide mounted upon the frame, a trigger engaging arm carried by the slide, and means for actuating the slide from the stock of the gun.

In testimony whereof I have signed my name to this specification in the presence of two subscribing witnesses.
